UNITED STATES PATENT OFFICE.

XAVER BRÜGGER, OF HOREN, SWITZERLAND.

WINDING FRAME.

Application filed April 24, 1922. Serial No. 556,213.

To all whom it may concern:

Be it known that I, XAVER BRÜGGER, a citizen of the Republic of Switzerland, residing at Horgen, Switzerland, have invented certain new and useful Improvements in Winding Frames; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The well-known winding frames provided with spools having on the side on which the drive is located a bearing which opens upwards, present the drawback that in winding up the thread which comes from the 20 thread holder, the spools vibrate, thus causing an unequal, hard and soft winding. The result thereof is that these spools must be re-wound.

25 The same drawback is inherent in the well-known weft winding frames in which a revolving spindle supported at one end carries the spools.

30 According to the invention, this drawback is eliminated by providing the ends of the driving shaft with friction disks with taper bores for the purpose of having coaxially supported, at one of their ends, two spools on which the thread is to be wound, the other ends of these spools being lodged 35 in disk bearings 16 provided with conical bearing surfaces and subject to the action of springs.

One embodiment of the invention is illustrated, by way of example, in the accompanying drawings, in which:

40 Fig. 1 shows the winding frame in front view, partially in section, and

Fig. 2 in a side view.

45 Figs. 3 and 4 show diagrammatically a modification of the thread holder in side view and in plan respectively.

50 The frame 1 (omitted in Fig. 1 for the sake of clearness) carries two bearing standards 2 with three bearings 3, 4 and 5 each. The central bearing 4 carries the driving shaft 6 for the spools 7. The drive is effected by means of cords from the shaft 8. Disks 9 are secured to both ends of the driving shaft 6, said disks fitting into the 55 pedestal of the bearing 4 so as to ensure an exactly axial rotation of the shaft. The

disks 9 are provided with taper bores 10. The shafts 11 of the bearings 3 and 5 are supported by the pedestals of these bearings at 12 and by the disks 14 which are adapted 60 to be shifted in axial direction and tightly fit into the bores 13 of said pedestals, helicoidal springs 15 being interposed between these two supports. The shafts carry, on their ends facing the spools 7, disks 16 65 rigidly connected with the shafts 11 and provided with the tapered bores 16'. In order to reduce the friction between the disks 14 and 16, balls 17 are interposed.

In order to enable spools of various 70 lengths to be wound, the bearings 3 and 5 may also be adapted to be shifted relatively to the central bearing 4.

If a spool is to be lodged between the shafts 6 and 11, one end of the spool is introduced into the taper bore of the disk 16 75 and the bearing pushed so far away as to allow the other end of the spool to be introduced into the taper bore of the disk 9 of the central bearing. It is obvious that 80 the drive of the spools could be effected from either side of the spools without any difficulty from the point of view of construction. In the same way, the central bearing could be adapted to be shifted ax- 85 ially.

In the upper portion of the winding frame the thread holders, reels for instance, are located. The reels could also be replaced by spools for example. The reels 18' and 18'' 90 supply material to the front spools whereas the reels 18''' and 18'''' supply material to the rear spools. This arrangement of the spools enables the length of the machine to be considerably reduced. In order to stop 95 the rotation of the spools in the case of an insufficient supply of material, the following arrangement is provided.

An angle lever 20 is fulcrumed pivotally about its axis 21 in the bearing 19. The 100 free end of the lever arm 20' faces the front surface 7' of the spool whereas the free end of the other lever arm 20'' of said angle lever bears against the free end of the lever arm 22' of another angle lever 22 fulcrumed 105 pivotally about the pivot 24. The lever arm 22' of the angle lever 22 carries on the top a pin 23 extending over the whole width of the reel. Should it now happen that the thread is not wound off the reel normally, 110 but is caught in the material on the reel and taken along in the direction of the arrow

Fig. 2, the thread strikes against the pin 23 whereby the angle lever 22 and thus the angle lever 20 as well is operated upon. The lever arm 20' now presses against the spool 5 and pushes it away from the driving shaft, the coupling between said shaft and the spool being thrown out of gear thereby.

Instead of a friction coupling, a clutch or claw coupling, for instance, could also 10 be applied between the driving shaft and the spool.

It happens that the thread running off the thread holder towards the spools is caught in the material not wound off, thus causing 15 the thread to be subject to an unequal stress, that is to say: it is subject to an excessive tensile stress in the case of such derangements whereby the structure of the thread is affected. The same occurrence takes place 20 when starting the machine, the thread holder being set in motion jerkily.

This drawback is avoided by supporting the thread holder in such a manner that it can be shifted in the direction of its height.

25 The journals 1^a, Figs. 3 and 4, of the thread holders 2^a lodge in the bearings 3^a of the arms 4^a of the pendulum 5^a, said bearings being open upwards. This pendulum is pivotally funcrumed at 6^a. The arm 30 7^a of the pendulum carries a counterpoise 8^a adapted to be shifted and fixed on arm 7^a for the purpose of balancing the pendulum with the thread holder.

The working of this method of supporting 35 the thread holder is readily comprehensible. Should a derangement occur in the supply of material whilst the machine is working, by preventing the thread from readily detaching itself from the other material, the increased tensile force acting upon the 40 thread sets the pendulum in a slight swinging motion downwards until the thread has loosened again, whereupon the pendulum

swings upwards again. The same occurrence takes place when starting the machine, 45 a greater stress then acting temporarily upon the thread owing to the state of inertia of the thread holder. Instead of the arrangement described, the journals of the thread holder could, for instance, rest on pillows supported by springs. 50

This method of supporting the thread holder can of course be also applied in weft winding frames.

I claim:

1. In a winding machine, a driven shaft having a friction cone at both ends, an alined yieldingly held friction cone opposite each end, and a bobbin having oppositely coned ends arranged to engage the cones on 60 the driven shaft and the alined friction cones.

2. In a winding machine, a driving shaft having a spool-engaging end, an alined spring-urged bearing for the opposite end of 65 a spool, an angle lever having one end arranged to engage the spool end at the driving shaft, a second angle lever having one arm arranged to engage the second arm of the first angle lever and its other arm arranged adjacent the path of the thread being wound, whereby when said thread hangs and does not evenly unwind, the angle levers are operated to release the driving connection between the driving shaft and spool. 70

3. In a winding machine, a driven shaft having a conical socket at its end, an alined shaft having a like socket, a spring to urge the latter socket toward the former socket and means for engaging a bobbin end to relieve the driving friction of the former driven socket upon undue thread tension. 75

In testimony that I claim the foregoing as my invention, I have signed my name.

XAVER BRÜGGER.
